sonville, Conn., a corporation of Massachusetts

Application May 19, 1934, Serial No. 726,483

9 Claims. (Cl. 28—38)

This invention relates to setting frames for winding a series of yarns side by side on a receiver or spool for use in weaving Axminster and like carpets and rugs.

According to the present practice in winding yarns on a receiver or spool and other preparation for weaving Axminster and similar fabrics, the usual presser roll exerts pressure on the yarn wound upon the receiver or spool and is under the influence of weights and levers or springs usually connected to a sliding member which supports the presser roll, and the compactness with which the receiver or spool is wound or the hardness of the full spool depends upon the pressure exerted by the presser roll.

When the required amount of yarn has been wound on the receiver or spool and it becomes necessary to disengage the yarn spool from the usual winding rolls, the operator must lift the presser roller by hand a distance sufficient to remove from the yarn spool the pressure of the presser roll and to provide clearance over the yarn on the receiver to swing the presser roll forward or to one side. Likewise, if it is desired at any time to insert or engage an empty receiver or spool when the presser roll is down in working position, the operator must again lift the presser roll by hand the full distance of the vertical lift or movement of the presser roll.

One of the objects of the present invention is to provide means to eliminate the labor fatigue of the operator in lifting the presser roll as described.

In accordance with the present invention mechanically operated power means is connected to the presser roll and is rendered operative at desired times to raise the presser roll from its contact with the wound yarn upon the receiver or spool, and since when a required amount of yarn has been wound upon the receiver and the receiver and its load are to be removed from the setting frame, the present invention provides for the automatic operation of the power means to raise the presser roll to provide a clearance between it and the yarn laid on the receiver such that the presser roll may be swung from its normal operative position to one side or frontwardly.

In accordance with another feature of the invention the power actuated means for raising the presser roll at any time desired is under the control of the machine attendant who may set the power means in operation.

The invention and novel features thereof will best be made clear from the following descrip-

tion and accompanying drawings of one good form thereof.

In the drawings:—

Fig. 1 is a side elevation of one type of Axminster setting frame containing the present invention, certain parts of the setting frame being omitted for clearness of illustration; and

Fig. 2 is a front view of the setting frame, with some of the parts broken away and taken at right angles to the view shown by Fig. 1.

The frame 1 of the machine may be of any convenient and appropriate character for supporting the operating parts, and mounted in suitable bearings on the machine frame is the main drive shaft 2 on which is loosely mounted the clutch pulley 3, Fig. 2, which may be driven from any suitable source of power by a transmitting power connection, such as a belt 4, Fig. 1.

In setting frames of the type shown, the winding mechanism or rolls for rotating the receiver are actuated from the main drive shaft when it is clutched to the clutch pulley 3 which is driven continuously, but since the transmitting mechanism between the main drive shaft and the winding rolls is well known and the details whereof form no essential part of the present invention, such transmitting mechanism is not herein illustrated.

Mounted in suitable bearings at the top portion of the machine frame are the winding rolls 5 and 6, between which the yarn receiver or spool 7 is supported and operated, it being understood, of course, that the series of yarns, as usual, are taken from appropriate sources of supply and led to the receiver 7.

Mounted in guide ways 8 on the machine frame are the presser roll supporting slides 9, one at each side of the machine, and on the upper portion thereof the presser roll is mounted, and in order that the presser roll may be turned from the position *x* to the position *y*, as indicated in Fig. 1, the supporting slides 9 are made in two parts connected pivotally at 11, the construction being such that when the presser roll has been raised a sufficient distance to provide a clearance between it and the mass of yarn wound upon the receiver, the presser roll may be moved from the position *x* to the position *y* by hand, as usual, whereupon the wound receiver or spool may be removed from the setting frame.

Mounted in suitable bearings 12 is the presser roll lifting shaft 13 which extends transversely of the machine frame and at its opposite ends has secured thereto arms 14 which are themselves connected at each side of the machine by the

rods 15 to the slides 9, as at 15', which support the presser roll, the result being that should the shaft 13 be turned the slides 9 and the presser roll mounted thereon may be raised the required amount desired.

Connected for rotative movement with the clutch pulley 3 is a sprocket wheel 18 which is connected by the sprocket chain 17 to a sprocket 19 loosely mounted on the presser roll lifting shaft 13. Associated with the sprocket wheel 18 is a roll lifting clutch 19, which may be of usual construction and, as shown, is of the Johnson jaw clutch type.

Pivotedly mounted at 20 on the standards 21 is the yoke 22, the pins 23 of which enter appropriate grooves in the clutch 19, and associated with the yoke 22 is the treadle 24, whereby the shifting movement of the clutch may be imparted to it by the machine attendant at appropriate times or when desired.

Operatively connected with the Johnson clutch is a sprocket wheel 25 which is connected by a sprocket chain 26 to a sprocket wheel 27 on the cam shaft 28, Fig. 2, the construction being such that upon operation of the sprocket wheel 25 through the clutch 19 the cam shaft 28 will be rotated.

It will be noted from Fig. 2 that the treadle mechanism may be operated at any time by the machine attendant and when it is in its upper position shown by full lines in Fig. 2, the clutch 19 is rendered inoperative, but when in dotted line or lower position, as indicated in Fig. 2, the clutch members are engaged and motion will be transmitted to the cam shaft, as described.

The cam shaft 28 carries at each end a presser roll lifting cam 29 which is operatively associated with pins or rolls 30, one on each of the presser roll slides 9, the construction being such that when the cam shaft 28 is rotated the presser roll lifting cams 29 will lift the presser roll from engagement with the yarn laid on the receiver.

From the construction thus far described it will be apparent that the operation of the cam shaft 28 and the lifting movement of the presser roll are under control of the machine attendant by manipulation of the treadle 24 which may be operated at any time during the winding operation when it is desired to lift the presser roll by power.

As hereinbefore intimated, one of the important features of the present invention consists in automatically lifting the presser roll by mechanical power when a predetermined amount of yarn has been wound upon the receiver, and as a conventional and well known form of means for determining the amount of yarn placed upon the receiver and causing the winding operation to be stopped, the yarns which are to be wound upon the receiver pass between the measuring rolls 31 and 32, and when the requisite amount of yarn has been wound upon the receiver the stop arm 33 is lifted about its pivotal connection 34, but since the measuring and winding stop motion is of well known construction and operation further details thereof appear unnecessary.

Connected to the stop arm 33 is a transmitter 35 which is connected to the clutch mechanism on the main drive shaft whereby the winding operation is stopped when the requisite amount of yarn has been wound upon the receiver, and since such mechanism and stopping means are of the conventional type and well understood by

those skilled in the art further elucidation of this feature appears unnecessary.

Connected to the stop arm 33 is a link 36 which at its lower end is connected with a short arm 37 of a lever 38 pivotally mounted on the machine frame at 39. The longer arm of the lever 38 is connected to a link 40, the lower end of which is connected to a rod 41 pivotally associated at 42 with the clutch controlling lever 43, the result being that when the stop arm 33 is raised, as hereinbefore described, and when the requisite amount of yarn has been wound upon the receiver the rod 41 will be depressed through the lever 38, link 40 and the connection 40', and thereby cause the clutch 19 to become operative to turn the cam shaft 28, as hereinbefore noted. The presser roll lifting cams 29 will thereupon raise the presser roll and provide a clearance between it and the yarn on the receiver.

The present invention also provides for stopping the operation of the lifting cams 29 when the presser roll has been raised to the maximum amount desired and to this end the rod 41 is provided with a slot 45 at its upper end which engages the pin 46 carried by an arm 47 secured to one of the slides 9 which support the presser roll.

As the winding operation proceeds the amount of yarn on the receiver gradually increases in amount and, of course, raises the presser roll while the latter still bears upon the yarn, and when the power actuated means has lifted the presser roll the desired amount to provide clearance between it and the yarn on the receiver, the pin 46 will rise in the slot 45 to the dotted line position, Fig. 2, thereby acting upon the clutch lever 43 to throw the clutch 19 out of operation with the presser roll raised to its upper limit.

It may be desirable at times to operate the presser roll lifting cams 29 during the winding operation by turning the cams under hand power and to this end the cam shaft 28 is provided with a sprocket wheel 48 about which passes the sprocket chain 49. The sprocket chain 49 likewise passes about a sprocket 50 mounted upon the machine frame and capable of actuation by the hand crank 51. It will be recalled that during the winding operation the power actuated means for lifting the presser roll 10 is out of action, that is the clutch 19 is disengaged from its companion member, so that it is possible to turn the presser roll lifting cams 29 by the hand means described at any time during the machine operation.

The crank arm 51 is preferably mounted upon an axis 52 while the sprocket wheel 50 may be selectively engaged with the crank arm by means of a clutch 53 against the stress of a light spring 54. This enables the crank arm 51 to remain idle until intentionally clutched to the sprocket 50, so that during the winding operation or the power actuation of the presser roll lifting means the crank arm remains idle.

Thus it will be seen that the present invention provides mechanical power means for raising the presser roll and provide a clearance between it and the yarn on the receiver, when the amount of yarn on the receiver has reached the desired condition, and it will be likewise noted that the machine attendant may at any time throw the power means into operation for lifting the presser roll. Furthermore, the presser roll lifting cams may be actuated by hand at any time during the winding operation while the

power means for lifting the presser roll is inoperative.

What is claimed is:—

1. In a setting frame for winding a series of 5 yarns side by side on a receiver, the combination of means for rotating the receiver, a presser roll to bear upon the yarns as they are wound upon the receiver, stopping means for stopping the winding operation when a predetermined amount 10 of yarn has been wound upon the receiver, power actuated mechanism for lifting the presser roll from the yarn load on the receiver, and connections between the stopping means and the power actuated mechanism for rendering said mechanism 15 operative to automatically lift the presser roll from the yarn load on the receiver when the stopping means stops the winding operation.
2. In a setting frame for winding a series of 20 yarns side by side on a receiver, the combination of means for rotating the receiver, a presser roll to bear upon the yarns wound upon the receiver, presser roll lifters, power actuated mechanism for moving the presser roll lifters to cause the presser roll to be raised from the yarn load, and means 25 for rendering the said power mechanism operative when a predetermined amount of yarn has been wound on the receiver.
3. In a setting frame for winding a series of 30 yarns side by side on a receiver, the combination of means for rotating the receiver, a presser roll to bear upon the yarns wound upon the receiver, presser roll lifter cams for raising the presser roll from the yarn on the receiver, power actuated means for operating the presser roll lifter cams, 35 and automatic means for setting the power actuated means in operation when a predetermined amount of yarns has been wound upon the receiver.
4. In a setting frame for winding a series of 40 yarns side by side on a receiver, the combination of means for rotating the receiver to wind yarns thereon, a presser roll to bear upon the yarns wound on the receiver, presser roll lifters for raising the presser roll from the yarn on the receiver, 45 and power actuated means rendered operative to actuate the presser roll lifters when a predetermined amount of yarn has been wound upon the receiver.
5. In a setting frame for winding a series of 50 yarns side by side on a receiver, the combination of means for rotating the receiver to wind yarns thereon, a presser roll to bear upon the yarns wound on the receiver, presser roll lifters for raising the presser roll from the yarn on the receiver, 55 power actuated means rendered operative to actuate the presser roll lifters when a predetermined amount of yarn has been wound upon the receiver and stopping mechanism for stopping the power actuated means for the lifters when the presser roll has been raised a predetermined distance.
6. In a setting frame for winding a series of 60 yarns side by side upon a receiver, the combination of means for rotating the receiver to wind the 5 yarns thereon, a presser roll to bear upon the yarn on the receiver, slides on which the presser roll is mounted, presser roll lifter cams which act upon the slides to raise the presser roll from the yarn on the receiver, power means for operating the lifter cams, yarn winding stop motion devices for stopping the winding operation when a predetermined amount of yarn has been wound upon the receiver, and means controlled from the winding stop motion devices for starting the power means in operation to cause the lifter cams to raise the presser roll from the yarn on the receiver.
7. In a setting frame for winding a series of 15 yarns side by side upon a receiver, the combination of means for rotating the receiver to wind the 20 yarns thereon, a presser roll to bear upon the yarn on the receiver, slides on which the presser roll is mounted, presser roll lifter cams which act upon the slides to raise the presser roll from the yarn on the receiver, power means for operating the lifter cams, yarn winding stop motion devices for stopping the winding operation when a predetermined amount of yarn has been wound upon the receiver, and means controlled from the winding 25 stop motion devices for starting the power means in operation to cause the lifter cams to raise the presser roll from the yarn on the receiver, and means actuated through the raising movement of the presser roll to stop the power means when the 30 presser roll has been raised a predetermined distance from the yarn on the receiver.
8. In a setting frame for winding a series of 35 yarns side by side on a receiver, the combination of winding means for rotating the receiver to wind the 40 yarns thereon, a presser roll to bear upon the yarns on the receiver, presser roll lifting cams for raising the presser roll from the yarn on the receiver, a main driving shaft for operating the winding means, a clutch shaft operatively 45 connected to the lifter cams, power means for operating the clutch shaft, and manually controlled means for connecting the clutch shaft operatively to its power means for raising the presser roll from the yarn on the receiver.
9. In a setting frame for winding a series of 50 yarns side by side on a receiver, the combination of winding means for rotating the receiver to wind the 55 yarns thereon, a presser roll to bear upon the yarns on the receiver, presser roll lifting cams for raising the presser roll from the yarn on the receiver, a main driving shaft for operating the winding means, a clutch shaft operatively connected to the lifter cams, power means for operating the clutch shaft, and manually controlled means for connecting the clutch shaft operatively to its power means for raising the presser roll from the yarn on the receiver and means controlled by the upward movement of the presser roll for disconnecting the power means 60 from the clutch shaft when the presser roll has been raised a predetermined amount from the yarn on the receiver.

ERNEST T. PHOENIX.
